13 Claims. (Cl. 196—104)

1
The present invention relates to a method of cracking or pyrolytically treating hydrocarbons to cause conversion thereof and to an improved cracking and coking oven for carrying out the said method, and, more particularly, the invention relates to a method of pyrolytically treating in a broad cracking and coking oven straight chain hydrocarbons, such as paraffin hydrocarbons occurring in petroleum and the like, to convert them into aromatic hydrocarbons, such as benzol, toluol, xylol, naphthalene, anthracene, and the like, while evolving vapors containing straight chain hydrocarbons from a fluid hydrocarbon mass and carbonizing the residue thereof into coke, and to the improved and novel apparatus or coke oven combination for carrying the aforesaid methods into practice.

Heretofore, various methods have been used for converting hydrocarbons into other hydrocarbon reaction products. Generally speaking, such conversions were formerly conducted in a variety of apparatus, including stills, cracking units, etc. In recent years, attempts have been made to conduct the pyrolytic conversion of petroleum hydrocarbons in ovens, such as coking ovens of the broad type. Various difficulties were encountered in these attempts and unsuccessful results or unsatisfactory results were obtained, including failures in certain instances. The most serious difficulties encountered were the choking up of channels and conduits with carbon, carbon residues, soot, and the like, the production of low yields of aromatic hydrocarbons, the poor coking of the residue of fluid hydrocarbon masses, and the poor quality and low grade of the aromatic hydrocarbons and coke which were produced. In attempts at actual commercial operations of the pyrolytic conversion of hydrocarbons, the results obtained were so poor that the operations were discontinued and were given up as commercially inadvisable or as industrial failures. Although various endeavors were made to overcome the foregoing difficulties, none, as far as I am aware, has been wholly satisfactory for commercial operation conducted on a full industrial scale.

The present invention involves the discovery that in cracking hydrocarbon vapors evolved during the coking of petroleum residue, for instance, for the production of aromatic hydrocarbons, it is necessary to control not only the direction of flow of the vapors and the temperature of the cracking fluids, but also the space velocity and the turbulence of the vapors. It has likewise been discovered that a cracking oven having a

2
special structure must be provided in order to properly carry out the pyrolytic conversion of hydrocarbons while at the same time heating fluid hydrocarbon masses to evolve hydrocarbon vapors and to carbonize the residue into good coke having acceptable qualities and properties.

It is an object of the present invention to provide for the pyrolytic conversion on a commercial or industrial scale of low cost hydrocarbon residual oils or the like to provide light oils, benzol, toluol, xylol and other aromatic hydrocarbons, together with coke, of a high quality and high yield.

It is another object of the invention to provide an improved process for the cracking of straight chain hydrocarbons and their conversion into aromatic hydrocarbons with a sufficiently high yield to warrant industrial operation.

A further object of the invention is to provide a new and improved combination of a coking oven and cracking chamber in which refractory materials are employed within a single structure capable of heating a fluid hydrocarbon mass to evolve hydrocarbon vapors therefrom and to carbonize the resulting residue therefrom into coke, thereby effecting the pyrolytic treatment of the evolved vapors containing straight chain hydrocarbons and their conversion into aromatic hydrocarbons.

It is also within the contemplation of the invention to provide a new and improved broad sole fired coking oven in which tar and carbon resulting from the pyrolytic treatment of hydrocarbons can be made into a high carbon coke having a true specific gravity of 2 or more, and suitable for the manufacture of carbon electrodes.

It is still a further object of the invention to provide a cracking and coking oven of novel and improved design providing a heating system for the distillation of heavy petroleum tar or the like and also a separate heating system within the same oven structure for the cracking of the oil vapors and the pyrolysis of paraffins for the production of aromatic oils and other aromatic hydrocarbons.

It is also an object of the invention to provide an improved broad cracking and coking oven having the walls of the vapor flues constructed with uneven surfaces to produce turbulence of the oil vapors in such a manner as to cause the oil vapors to contact the hot wall surfaces, whereby effective pyrolytic treatment of hydrocarbons can be conducted.

Moreover, it is an object of the invention to provide a cracking and coking oven involving novel

and improved combinations in which an increased and positive control of the flow and velocity of the oil vapors through the vapor flues is maintained, and in which positive control of the air to be preheated is provided, together with positive control of the waste gas from the oven, the said combinations involving an arrangement of structural elements which are capable of causing the air being heated to flow through horizontally-disposed recuperator tubes and of causing the waste gas which is being cooled to flow around the recuperator tubes, whereby uniformity of flow and an effective change of temperature is imparted to the air from the sensible heat in the waste gases.

Furthermore, it is an object of the invention to provide a broad cracking and coking oven having a multiplicity of straight, independent heating flues extending parallel to the oven and divided on the center line of the oven, so that the heating flues connect on each side of the center line of the oven with two separate recuperators, thus providing for a continuous stream of the heating gases throughout the whole heating system from each flue burner to the recuperators and the stack.

The invention likewise contemplates the provision of an oven structure in which flues are employed below each floor heating flue for the recirculation of the waste hot gases from each heating flue, for the purpose of providing more uniform heating of the oven floor by extending the flame length by means of the recirculated waste gases.

It is still another object of the invention to provide a structure in which the recirculation of the waste gases passing through and around the flames from the floor burners reduces the flame temperature due to the presence of water vapor in the waste gas.

It is a further object of the invention to provide a broad sole fired oven having a multiplicity of burners and heating flues under constant and uniform temperature without having to reverse the flow of the waste gases, through structural means for preheating the air.

Still another object of the invention is to provide an improved oven construction for the production of coke and the cracking of hydrocarbon oils, in which cracking flues are so located that a separate long heating flue is directly below and parallel to each individual cracking flue, and in which each oil vapor cracking flue is supplied with an air jet for the purpose of burning out any carbon which might collect in each oil vapor flue.

With these and other objects in view, the invention comprises the various features and combinations hereinafter more fully described and more particularly defined in the annexed claims.

The invention is illustrated in and described in connection with the accompanying drawings, in which:

Fig. 1 is a vertical longitudinal sectional view showing a coking oven, tubular recuperators, upper heating flues, lower heating flues, waste gas recirculation flues and other flues in which the oil or other hydrocarbon vapors are cracked, gas manifolds, and piping to the upper and lower longitudinal heating systems, waste gas outlets and cracked oil vapor off-takes.

Fig. 2 illustrates a vertical cross-sectional view of an oven showing the vertical recuperators' lower heating system, waste gas recirculation flues, upper heating flues, flues in which the oil vapors are cracked, the air supply to the recuperators, and the air and oil ports leading into the oven;

Fig. 3 depicts a vertical cross-sectional view

taken on the section line 3-3 of Fig. 1, in which the flow of air is indicated through the tubular recuperators by means of arrows, and the flow of oil or other hydrocarbon vapors directly from the oven to the vapor off-take is also indicated by means of arrows;

Fig. 4 is a vertical cross-sectional view taken on the section line 4-4 of Fig. 1, in which the travel of the waste gases from the lower heating system into the recuperator is indicated;

Fig. 5 shows an end view of the oven from the right in Fig. 1, taken from the section line 5-5, showing the gas and air piping to the lower and upper heating system, and air pipe connections to the vapor cracking flues;

Fig. 6 is a horizontal sectional view of the recuperators taken on the section line 6-6 of Fig. 1, in which the flow of waste gas and incoming air is indicated by arrows;

Fig. 7 depicts a horizontal sectional view taken on the section line 7-7 of Fig. 1, in which the flow of waste gas into the recuperators is indicated by arrows;

Fig. 8 is a horizontal sectional view taken on the section line 8-8 of Fig. 1, showing the flues connecting the air flues from the recuperators with the lower heating flues;

Fig. 9 illustrates a horizontal sectional view taken on the section line 9-9 of Fig. 1, showing the waste gas recirculation flues, in which the flow of the waste gas to the preheated air flues is indicated by arrows;

Fig. 10 is a horizontal sectional view taken on the section line 10-10 of Fig. 1 directly below the floor of the oven and showing the lower heating flues;

Fig. 11 depicts a horizontal sectional view taken on the section line 11-11 of Fig. 1, showing the longitudinal flues of the upper heating system directly below the floor of the oil vapor cracking flues;

Fig. 12 shows a horizontal sectional view taken on the section line 12-12 of Fig. 1, showing the oil vapor cracking flues extending longitudinally of the oven, the view showing in detail the irregular surfaces of the cracking flues; and

Fig. 13 illustrates a diagrammatic perspective view of my novel oven clearly showing the flow of gas, air, fuel, steam, oil or tar, etc., therein.

Broadly stated, the present invention contemplates the pyrolytic conversion of hydrocarbons for the production of aromatic hydrocarbons, such as benzol, toluol, xylol and the like, by the heat treatment of petroleum residues or other hydrocarbon oils, tars, or materials to produce hydrocarbon vapors or gases in the manner hereinafter more fully set forth. In accordance with the invention an apparatus is provided including an oven structure and cracking chambers or flues in which the pyrolytic conversion can be controlled within a temperature range to effect the desired conversion.

By controlling the direction of flow of the hydrocarbon vapors in the oven and through the cracking chamber, and by controlling the temperatures in the cracking chamber, while at the same time controlling the space velocity and turbulence of the vapors, relatively high yields of aromatic hydrocarbons can be obtained. In carrying the foregoing operation into practice, large quantities of gases are produced from the petroleum residue or the like, under treatment, as well as tar and carbon which are converted into useful coke. All of the foregoing operations are conducted within a single structure having a novel

combination of cooperating elements by which improved results are obtained, eliminating certain operating difficulties of prior operations and substantially reducing the cost of manufacture of the products obtained thereby. A high yield of aromatic hydrocarbons and the production of electrode coke can be obtained by the processing of 8½ degree API residuum oil, for example, by charging the oil into the oven at 700° F. and cracking the hydrocarbon vapors produced therefrom at a temperature of about 1350° F., for instance, in the cracking chamber, or cracking flues, hereinafter described and the subsequent recovery and separation of components of the reaction produced.

The single novel structure or apparatus employed in carrying out the pyrolytic conversion of the hydrocarbons includes a broad cracking and coking oven which, in a commercial installation can be about 42 feet long and about 10½ feet wide, being rectangular at the base of the oven and arched in the manner shown more particularly in Fig. 2 of the drawings, which is combined with a heating system adapted to operate with either rich fuel gas, such as coke oven gas, oil gas, or with liquid fuels, such as fuel oils, tars, and the like, and which can be combined with preheated air from recuperators and mixed with recirculated hot waste gases. Housed within the upper part of the oven structure is a cracking chamber provided with an independent heating system which can be so controlled as to obtain the desired temperature in the floor and side walls of the oil cracking flues. The entire brick work structure is preferably encased in a metal shell, such as a welded steel casing, whereby the interior of the oven may be operated under pressure or under sub-atmospheric pressure, as desired.

Generally speaking, the oven heating system below the oven floor preferably consists of any suitable number of flues, depending upon the oven width employed, the flues being preferably arranged longitudinally of the oven to support and heat the floor thereof. Each longitudinal flue is preferably divided at its transverse center line so that the waste gas from each half flue is diverted into the recuperators situated below and parallel to the corresponding half of the oven. The two sets of horizontal recuperators located below and parallel to the oven and to the heating flues are in constant use during the operation of the apparatus to supply heated air to opposite ends of the floor heating flues and to constantly receive the hot waste products of combustion which, in turn, pass to the oven waste-gas stack.

Referring more in detail to the drawings, it will be understood that the cracking and coking oven embodying my invention comprises an arched rectangular broad coking chamber O—1, in which the fluid hydrocarbon mass, such as oil residue, tar or the like, is heat treated and distilled, leaving carbon, which is one of the products of the reaction or heat treatment, on the oven floor to be coked. Superimposed upon the coking chamber are flues VF—1, in which vapors from the mass of fluid hydrocarbons are heat treated. The hot oil or tar is charged into the coking chamber O—1 through charging ports P—1 in both sides of the side walls of the oven. The oil vapors pass from the coking chamber O—1 through damper-controlled off-take ducts D, at both sides of the oven, into a top plenum chamber P—2, and thence through ducts D—1, controlled by dampers D—1, into vapor heat-treating flues VF—1 and

out of the oven structure through breeching B—1 and wash-oil valve V—2, into a vapor flue V—3 to a conventional or standard by-product recovery apparatus well known to those skilled in the art.

At the beginning of the distillation process, for a period of perhaps ten to twenty minutes, it is desirable to take off the uncracked heavy oil vapors through a duct D—2 (see Fig. 3) at each 10 side of the oven, the ducts being provided with dampers D—3 which control the passage of the vapors into the vapor breeching B—1. The flow or travel of the oil vapors at the start of the oven operation can be controlled by closing the dampers D—4 (see Fig. 2) in both of the ducts D, the dampers D—3 (see Fig. 3) in both of the ducts D—2 being open, thus permitting the vapors to flow directly to the breeching B—1, through the wash-oil valve V—2, to the vapor main V—3, and from thence to the by-product recovery apparatus. After the floor of the oven is covered with the hydrocarbon oil or tar to be treated, and coking has started, dampers D—4 in both of the ducts D may be opened, and the dampers D—3 20 in both of the ducts D—2 can be closed. The flow or travel of the oil vapors then takes place through the oil cracking vapor flues VF—1 to the breeching B—1, through the wash-oil valve V—2, to the vapor main V—3, and to the by-product recovery apparatus. During the entire oil cracking operation, the oven is sealed against the admission of air by means of oven doors OD—1, provided at the coke pusher end (see left end in Fig. 1) and also at the coke discharge end of the oven. 30 Beneath each half of the coking chamber O—1 (see the left and right halves, referring to Fig. 1) and running parallel to the length thereof are heating flues 1, 2, 3, 4, 5, 6, 7, 8 and 9 (see the left half of Fig. 1, and Fig. 3) and 1—F, 2—F, 40 3—F, 4—F, 5—F, 6—F, 7—F, 8—F and 9—F (see the right half of Fig. 1 and Fig. 2), which are preferably arranged horizontally, and each half flue is preferably independent of the adjoining flues. The flues are separated from each other by longitudinal partition walls as is indicated in Figs. 2 and 3 of the drawings. The heating flues 1 to 9 (Fig. 3) and 1—F to 9—F (Fig. 2) are provided at the outer ends thereof with suitable heating means, such as gas burners B—2 and B—3 45 (see Fig. 1), which can be supplied with fuel in a manner to be hereinafter described. Below each floor heating flue is a recirculation flue RC, for the recirculation of hot waste gases from and to each floor heating flue, so as to produce, during the operation of the apparatus, a long flame and to provide uniform heating of the oven floor.

Below the recirculation flues RC on each half of the oven are located two sets of recuperators R—1, R—2 and R—3, R—4, the recuperators R—1 and R—2 being in series, and R—3 and R—4 being also in series, but the two sets in series operate independently of each other, as will be apparent from the detailed description of the operation of the apparatus hereinafter more fully set forth. 60 The tubes of the recuperators are preferably constructed of silicon carbide, which permits the almost instantaneous transfer of the sensible heat from the hot waste gas through the wall of the tubes to the air to be preheated.

The recuperator R—3 is connected with the floor heating flues 1 to 9, inclusive, through ducts D—5 (see Fig. 1), and the recuperator R—1 is connected with the floor heating flues 1—F to 9—F, inclusive, through ducts D—6 (see Fig. 1).

The recuperators R-2 and R-4 are connected with the waste gas flue C-1 (see Fig. 1 and Fig. 4).

It will be understood that the portion of the apparatus heretofore described in detail relates to the lower half of the oven unit, which is used primarily for the distillation of the hydrocarbon oil or tar and for the coking of the residue. The upper portion of the apparatus is designed particularly for the treatment of oil vapors from the hydrocarbon oil or tar to effect cracking or the pyrolytic heat-treatment of the hydrocarbon vapors for the production of aromatic oils or compounds. The oven sections or parts are designed to be operated as a single unit, but the oil vapor cracking flues VF-1 may be closed off, if desired, by means of dampers D-4 (see Fig. 2) and the oven may then be operated solely as a distillation and coking oven for the production of coke and high B. t. u. oil gas.

The heat-treating flues VF-1 (see Figs. 1, 2, 4 and 12) which may consist of any desired number of flues, as may be required to handle the volume and velocity of the oil vapors produced, are preferably arranged horizontally, or in a horizontal position longitudinally of the oven, and may be separated from each other by longitudinally arranged silicon carbide partition walls W (see Fig. 12), each of which has a multiplicity of projections T which serve to cause turbulence of the oil vapors during passage of the vapors in contact therewith and to produce more intimate contact with the wall surfaces.

Each duct D-1 is preferably provided with regulating dampers D-7 (see Figs. 1 and 2) for the purpose of controlling the volume of oil vapors from the plenum chamber P-2 to each of the vapor cracking flues VF-1. Each vapor flue is preferably provided with an air inlet A-1 from a manifold A for burning carbon in the cracking flues. Beneath each vapor cracking flue, and arranged in a horizontal position longitudinally of each vapor flue VF-1, is a heating flue CF-1 (see Figs. 1, 2 and 11). These heating flues CF-1 are preferably single and are separated by partition walls W-1, as shown in Fig. 11. Each heating flue is preferably provided with a separate gas or oil burner B-4, which may be supplied with gas or oil from a manifold B. The products of combustion from all of the heating flues CF-1 discharge into a flue C-2 (see Figs. 1 and 11) and through a stack flue C-3 to a waste-heat boiler, or to the atmosphere as desired.

When hydrocarbon vapors from the charge of residue oil or tar have been evolved and there are substantially no more vapors to heat-treat in the flues VF-1, and the carbonaceous residue has been thoroughly coked, then the coke product is ready to be pushed from the oven into a standard quenching car or other suitable container.

The circulation of gases through the apparatus is as follows:

Hot waste gas from the floor heating flues 1 to 9 inclusive at the left side of the oven in Fig. 1, flows through ducts D-5, then around the silicon carbide tubes SC in the recuperator R-3, then around the tubes SC in the recuperator R-4 and into the stack flue C-1. Simultaneously, hot waste gas from the heating flues F-1 to F-9, inclusive, at the right side of the oven in Fig. 1, flows through the ducts D-6 into the recuperator R-1, around the silicon carbide tubes SC therein, then through the passageway at the right into the recuperator R-2 around the sili-

con carbide tubes therein and then into the stack flue C-1.

The air required for combustion in the floor heating flues enters the apparatus through the duct A-2 (see Fig. 2) and passes through duct D-8, from which it is distributed through the silicon carbide tubes SC in the recuperator R-2, where it is preheated, and then passes into the duct or passageway D-9 and is distributed therefrom into the silicon carbide tubes SC of the recuperator R-1, where the temperature is normally raised to about 1500° F. The air then passes from the tubes in the recuperator R-1 into the duct D-10, from which it passes into duct D-11 (see Figs. 2 and 8) and from thence to ducts D-12, then upward through ducts D-13, then upward through the lateral ducts or passageways D-14 (see Fig. 1) into the heating flues 1 to 9 inclusive, and 1-F to 9-F inclusive, under the oven floor.

The volume of preheated air to each floor heating flue may be regulated as desired by means of dampers D-15 (see Fig. 1), the air serving to support combustion of the oil or gas burned by the burners B-2 at the right end of the oven in Fig. 1, and B-3 at the left end of the oven, as shown in Fig. 1. Each of the burners B-2 and B-3 is operated under pressure and has an inspirator action, which not only causes forward flow of the preheated air, but also draws a large volume of hot waste gas from each floor heating flue through openings or ducts CF-2 (see Fig. 1) into the recirculation flue RC and causes the hot waste products to mix with the air in the duct D-14 (see Figs. 1 and 9) directly below each burner B-2 and B-3. At the inner end of the recirculation flues are projections PF (see Fig. 1) which extend upwardly into each heating flue and serve to deflect a volume of the hot waste gas into each recirculating flue RC.

The improved method embodying the present invention may be carried out in any appropriate oven. For instance, a structure similar to that described and illustrated in my co-pending application Serial No. 510,760 may be used, but the novel system herein described, having oil vapor cracking flues located directly above separate heating flues longitudinally of the vapor flues and the oven, has demonstrated the value of the improved method in actual practice in the cracking and coking oven hereinabove described.

The following is a brief description of the operation of the preferred embodiment of my invention when applied to the heat treatment of residue oil known as Dubbs A. P. I. gravity heavy residuum oil, for example, for the production of either electrode coke or domestic coke from the carbon content of the heavy oil, in heat-treating the oil vapors for the recovery of aromatic oils, such as benzol, toluol, xylol and solvent naphtha. The heavy oil, or oil tar, is preferably preheated to about 700° F. and is then continuously sprayed into the coking chamber at various points through ports P-1. The oil rapidly covers the entire oven floor or the carbonized residue thereon, and vaporization of the hot oil begins substantially immediately, together with the carbonizing of the residue and the pyrolytic treatment of the oil vapors proceeds, as described.

The process can be advantageously conducted using an eight hour operating cycle divided substantially as follows: The oven can be maintained "on stream," that is, with oil being continuously fed into the oven, during a period of about five and one-half hours; the time required for coking

is about seven hours, including the time that the oven is "on stream"; and the time required for pushing the coke from the oven and for luting or sealing the oven doors and burning the deposited carbon in the cracking flues is about thirty minutes, thus requiring substantially eight hours to complete the cycle. The carbon which is deposited over the surfaces of the vapor cracking flues during the cracking operation is quite fluffy and is readily burned off by blowing air into each vapor cracking flue through pipes A-1 (see Figs. 1 and 5) during the last thirty minutes of operation of the cycle. The coke which is produced has a true specific gravity, as distinguished from the apparent specific gravity, of about 2.0, or more, and may contain from upwards of about 90 to about 98% or so of fixed carbon, together with a small amount of volatile matter, and up to about 0.5% of ash. The following specification has been satisfied by my coke:

	Maximum percentage
Moisture	0.0
Volatile matter	0.5
Ash	0.45
Silicon	0.06
Iron	0.06
Calcium	0.00
Sulphur	0.40
Soluble salts	0.05
Carbon	98.48
Total	100.00

Real density or true specific gravity minimum

2.00

In the coking of any carbonaceous material, a certain percentage of fine or small particles of coke, known as breeze, is produced. This breeze is mixed with the petroleum residue referred to hereinbefore and is coked as previously described. The product can be sold as electrode coke or as a fuel.

The control of the floor temperature of the oven is necessary in order to satisfactorily regulate the steps of the process from the point at which the oil, tar, or the like is sprayed over the oven floor surface. In order to maintain control of the oven floor temperature, the gas to the burners in the heating flues 1 to 9, and 1-F to 9-F, under the floor of the oven is reduced in volume so as to reduce the temperature of the floor from about 2,000° F. to about 1,350° F. The temperature of the oven floor drops rapidly as the volume of fuel gas is reduced, and as the oil covers the floor of the oven, the volume of fuel gas to the heating flues is increased. Furthermore, as the depth of the coke over the floor of the oven increases, more gas is used at the burners to raise the temperature as required for coking the incoming oil which is being deposited, until at the end of the oil input, when the coke bed is about seven inches thick on the average, then the temperature in the heating flues is raised to an average of about 2750° F. which is necessary to complete the coking of the oil carbon residue on the top surface of the coke.

Referring now more particularly to the production of aromatic hydrocarbons from the straight chain hydrocarbons evolved in the oven during the distillation process, it has been found in actual practice in a broad oven of my invention that the exothermic reaction temperature relating to the conversion of straight chain hydrocarbons to aromatic hydrocarbons will average about 1350°

F., and that contact of the oil vapors with the hot surfaces of the cracking flues VF-1 is required in order to bring about the conversion of straight chain hydrocarbons into aromatic hydrocarbons. To insure contact of the hot hydrocarbon vapors with the hot cracking and heat-treating surfaces of the cracking flues, means are provided on the surfaces thereof for causing turbulence of the hot oil vapors. To provide for an average temperature of about 1350° F. within the cracking flues VF-1, the floor and side walls of each of the vapor flues are preferably constructed of silicon carbide in order to attain almost instantaneous transfer of heat to the oil vapors, and to maintain the required uniform temperature of the vapor contacting surfaces. It has been found as a result of experiments and tests that it is necessary to cause the hydrocarbon vapors to intimately contact the hot surfaces of the oil cracking flues in order to effect the conversion of straight chain hydrocarbons into the desired aromatic hydrocarbons. The upper heating system heretofore described, including the superimposed vapor cracking flues, has been designedly incorporated in connection with the oven structure of my invention as a means of heating each vapor cracking flue by means of heat radiated into each vapor cracking flue. By means of the structure as shown and described, turbulence of the oil vapors in passing through the oil vapor cracking flues is produced, resulting in the intimate contact of the oil vapors with the hot wall surfaces.

The present invention provides a new design of a cracking and coking oven, which in actual practice can be from about thirty to forty feet long at the inside, between the oven doors OD-1, about 10½ feet in width, from the pusher end door to the discharge end side of the oven, and about 2½ feet in height at the spring line of the arch over the coking chamber and about 4 feet 8 inches in height under the arch at the center of the oven. The heating flues of the cracking chamber preferably have a free cross-sectional area of about 100 square inches. It will be understood that although the cracking chamber VF-1 is heated in part from the heat coming from the oven O-1, the independent heating flues CF-1 provide the additional heat required for the cracking and heat-treating of the hydrocarbon vapors. Each separate heating flue is also preferably provided with a means of control for the amount of fuel to be burned by means of the burners B-4, and thus of the amount of heat evolved for radiation and conduction to the vapors in the vapor cracking flues VF-1.

In carrying the process into practice, the temperature of the floor and walls of the cracking flues are preferably maintained at about 1800° F., thus providing a cracking flue temperature of about 1350° F. for the conversion of straight chain hydrocarbons to aromatic hydrocarbons, such as light oils, from which benzol, toluol, and xylol can be obtained.

For the purpose of evolving hydrocarbon vapors from the oil residues, tar, and the like, in the oven O-1, a controlled amount of heat is supplied by the heating flue system under the oven floor and any desired number of heating flues may be employed as may be required in any given installation.

The theory underlying the pyrolysis of hydrocarbons is not completely understood at the present time and the mechanism of the chemical reactions involved is very complex. In the conver-

sion of hydrocarbons, a variety of reactions occurs including decomposition, polymerization, and side reactions. The aforesaid reactions include those of the endothermic type as well as those of the exothermic type. Generally speaking, the decomposition of hydrocarbons belongs to the endothermic type, whereas those relating to polymerization belong to the exothermic type. In the conversion of straight chain hydrocarbons to aromatic hydrocarbons it appears that the first reactions are of the decomposition variety and are subsequently followed by those of a polymerizing variety which may also be accompanied with various side reactions. Although many factors are involved, it appears that the more important are temperature, time or space velocity, turbulence of the vapors, pressure, concentration, and contacting surfaces. Under certain conditions, including the use of appropriate catalysts, such products as butadiene and other hydrocarbons may be formed. By controlling the conditions in the cracking and heat-treating chamber a variety of products can be produced. It is understood, however, that the present invention is not to be restricted to and dependent upon any theory including the foregoing.

Although the present invention has been disclosed in connection with a preferred embodiment thereof, variations and modifications may be resorted to by those skilled in the art without departing from the true spirit and scope of the invention as disclosed in the foregoing specification and defined by the appended claims. Thus, for instance, the present method, and the coking and cracking oven above described, may be used for coking and the distillation of coal tar and coal tar pitches, for the recovery of a variety of compounds including creosote and tar acids, and for the recovery of volatile products including volatile oils. Moreover, the novel process and oven heretofore described may be used for heating of oil shales and for the recovery of various by-products including oil and fractions thereof.

Having thus described the invention, what is claimed as new is:

1. A cracking and coking oven for the pyrolytic treatment of hydrocarbon material to produce aromatic hydrocarbons and coke therefrom, which comprises a longitudinally-extending main coking chamber, a series of heating flues directly below the floor of said chamber arranged side by side on each half of the chamber, means for heating each of said heating flues, a recirculation flue below each of said heating flues and communicating therewith at the end portions thereof, a recuperator set below each longitudinal half of said main coking chamber, said recuperator sets having hollow heat-transmitting tubes therein adapted for the passage of air therethrough, said tubes extending transversely to the longitudinal direction of said main chamber, a passageway extending from said heating flues through the recuperator sets around said tubes to a waste-gas discharge flue, means for passing air through said tubes into said heating flues so as to preheat the air passing thereto, a series of cracking flues above said longitudinally-extending main coking chamber, a passageway for oil vapors from said main chamber into said series of cracking flues, a series of heating flues above said main coking chamber and immediately below said cracking flues for heating said cracking flues, means for discharging cracked hydrocarbon vapors from said cracking flues, 75

means for condensing a portion of said vapors, and means for recovering the uncondensed portion of the vapors.

2. A refractory cracking and coking oven of the broad rectangular type for the pyrolytic treatment of hydrocarbon oils to produce aromatic hydrocarbons and coke therefrom, which comprises a longitudinally-extending main refractory coking chamber having a width greater than its depth, refractory chamber heating flues directly below the floor of said coking chamber on each longitudinal half thereof extending longitudinally of the chamber, means for heating each of said heating flues, a refractory recirculation flue below each of said heating flues and communicating therewith at the end portions thereof, a refractory recuperator set below each longitudinal half of the said longitudinally-extending main chamber, said recuperator sets having hollow heat-transmitting tubes therein and extending transversely therethrough, a passageway extending from said heating flues through the recuperator sets around said tubes to a waste-gas discharge flue, means for passing air through said tubes into said heating flues so as to preheat the air passing thereto, a series of cracking flues located above and incorporated within the refractory roof of said longitudinally-extending main coking chamber, each of said cracking flues extending longitudinally of said coking chamber for substantially its entire length, means for passing a hydrocarbon oil into the main coking chamber, a passageway for oil vapors from the said main chamber into the said series of refractory cracking flues, means independent of the chamber heating flues for maintaining the temperature underneath the cracking flues such as to produce aromatic hydrocarbons from the hydrocarbon vapors passing thereto during the portion of the pyrolytic treatment in which hydrocarbon vapors are produced, means for discharging the hydrocarbon vapor product from said cracking flues, means for condensing a portion of the said discharged vapor product, means for collecting the uncondensed portion thereof, means for discontinuing the flow of hydrocarbon oil to said main coking chamber to arrest the vapor-generating portion of the pyrolytic treatment and means for passing air into the said cracking flues after the vapor-generating portion of the treatment is arrested so as to burn off collected carbon in the said cracking flues.

3. A cracking and coking oven for the pyrolytic treatment of hydrocarbon oils to produce aromatic hydrocarbons and coke therefrom which comprises a longitudinally-extending main coking chamber, means for passing a hydrocarbon oil to be pyrolytically treated into said main coking chamber during the oil vaporizing portion of said treatment, heating flues directly below the floor of said chamber on each longitudinal half thereof, means for heating each of said heating flues to provide a coking temperature during the coke forming portion of said treatment, a recirculation flue below each of said heating flues communicating therewith at the end portions thereof, a recuperator set below each longitudinal half of the said longitudinally-extending main chamber, said recuperator sets having hollow heat-transmitting tubes therein extending transversely therethrough, a passageway extending from the heating flues through the recuperator sets below each half of said main chamber around said tubes to a waste-gas discharge flue, means for passing air to said tubes and through the tubes of each

recuperator set into said heating flues so as to preheat the air passing thereto, a series of cracking flues above said longitudinally-extending main coking chamber, said cracking flues having partition walls of uneven surfaces at the interior of the flues to cause turbulence of the oil vapors passing therethrough in contacting with the uneven surfaces, a passageway for oil vapors from said main chamber into said series of cracking flues, a series of cracking flues heating flues above said main coking chamber for independently heating said cracking flues, means for passing hot products of combustion through said cracking-flue heating flues to control the temperature of said cracking flues during the oil vaporizing portion of said treatment, means for drawing off cracked hydrocarbon vapors from said cracking flues while the temperature thereof is maintained within temperature limits to produce substantial proportions of aromatic hydrocarbons during said coke-forming portion of said treatment, means for condensing a condensable portion of said cracked hydrocarbon vapors, means for collecting the uncondensed portion of said vapors, means for removing coke from said main coking chamber and means for passing air into said cracking flues to burn collected carbon therein during the remaining portion of said treatment.

4. A cracking and coking oven for the pyrolytic treatment of hydrocarbon oils to produce aromatic hydrocarbons and coke therefrom which comprises a longitudinally-extending main coking chamber, means for passing a hydrocarbon oil to be pyrolytically treated into the said chamber during a portion of said treatment, heating flues directly below the floor of said chamber on each longitudinal half thereof, means for heating each of said heating flues to provide a temperature on the floor of said chamber sufficient for the production of coke from said hydrocarbon oil and to vaporize the uncocked portion of said hydrocarbon oil, a recirculation flue below each of said heating flues communicating therewith at the end portions thereof, a recuperator set below each longitudinal half of said longitudinally-extending main chamber, said recuperator sets having hollow silicon carbide tubes therein extending transversely therethrough, a passageway extending from the heating flues on each longitudinal half of said main chamber through the adjacent recuperator sets around said tubes therein to a waste-gas discharge flue, means for passing air into and through said tubes of the recuperator sets to preheat the air passing into said heating flues, damper means for independently controlling the passage of air through said tubes in the recuperator sets on each longitudinal half of said main chamber, a series of cracking flues above said longitudinally-extending main coking chamber extending longitudinally thereof, said cracking flues having projections on the interior walls thereof to cause turbulence of oil vapors passing therethrough and to provide intimate contact thereof with said projections to produce rapid heat transfer to said vapors, a passageway for oil vapors from the said main chamber into said series of cracking flues, means for controlling the volume of vapors through said passageway to each of said cracking flues, a series of cracking-flue heating flues above said main coking chamber and immediately below said cracking flues for heating the same, means for passing hot products of combustion through said cracking-flue heating flues to provide a temperature therein within a range sufficient for the production of

aromatic hydrocarbons from said oil vapors, means for discharging hydrocarbon vapors from the said cracking flues, means for controlling the pressure within said main chamber and said cracking flues during said pyrolytic treatment so as to provide for maximum production of aromatic hydrocarbons at the temperature of operation within said cracking flues, means for condensing a condensable portion of said hydrocarbon vapors, means for collecting the uncondensed portion of said hydrocarbon vapors and means for passing into said cracking flues to burn collected carbon therein during a portion of the cycle after the pyrolytic treatment of said hydrocarbon oils.

5. In a refractory cracking and coking oven of the broad rectangular type for the pyrolysis of hydrocarbons including the conversion of straight chain hydrocarbons into aromatic hydrocarbons containing only a small amount of paraffins and the production of coke having a high density of at least 2.0, that improvement which comprises a series of refractory heating flues directly below the floor of the coking oven, a series of refractory recirculation flues below said heating flues and communicating therewith at the end portions of the recirculation flues, means for passing a hydrocarbon oil into the coking oven, an elongated refractory cracking flue incorporated in the roof above the said oven and having an extended passage therethrough for the conversion of straight chain hydrocarbons into aromatic hydrocarbons containing only a small amount of paraffins, an off-take duct connecting said oven with said cracking flue for conducting gases and vapors from said oven to said flue, refractory heating flues independent of said oven heating flues and located in the roof of said coking oven and directly underneath said cracking flues to furnish independent heat thereto, and means to control said independent heat to regulate the temperature of said cracking flues to effect a maximum conversion of said straight chain hydrocarbons into aromatic hydrocarbons containing only a small amount of paraffins.

6. In a refractory cracking and coking oven of the broad rectangular type for the pyrolysis of hydrocarbons including the conversion of straight chain hydrocarbons into aromatic hydrocarbons containing only a small amount of paraffins and the production of coke having a density of at least 2.0, that improvement which comprises a series of refractory heating flues directly below the floor of the coking oven, a series of refractory recirculation flues below said heating flues and communicating therewith at the end portions of the recirculation flues, means for passing a hydrocarbon oil into the coking oven, an elongated refractory cracking flue incorporated in the roof above said oven and having an extended passage therethrough for the conversion of straight chain hydrocarbons into aromatic hydrocarbons containing only a small amount of paraffins, means for regulating the temperature of the floor of the coking oven so as to control the coking of said hydrocarbon oil, an refractory off-take duct connecting said oven with said cracking flue for conducting gases and vapors from said oven to said flue, refractory heating flues independent of said oven heating flues and located in the roof of said coking oven and directly underneath said refractory cracking flues to furnish independent heat thereto, and means to independently control the heating of said latter heating flues to regulate the temperature of said cracking flues to effect a maximum conversion of said straight chain hydrocarbons into aromatic hydrocarbons containing only a small amount of paraffins.

drocarbons into aromatic hydrocarbons containing only a small amount of paraffins.

7. In a refractory cracking and coking oven of the broad rectangular type for the pyrolysis of hydrocarbons including the conversion of straight chain hydrocarbons into aromatic hydrocarbons containing only a small amount of paraffins and the production of coke having a density of at least 2.0, that improvement which comprises a series of separated main refractory heating flues directly below the floor of said coking oven on each longitudinal half thereof and extending longitudinally of the chamber, a series of refractory recirculation flues positioned below said heating flues so as to communicate therewith at the end portions of the recirculation flues, means for spraying a hydrocarbon oil onto the floor of said coking chamber, an elongated cracking flue, incorporated in the roof above the said oven, having walls of refractory material with uneven surfaces therein and having an extended passage therethrough for the conversion of straight chain hydrocarbons into aromatic hydrocarbons containing only a small amount of paraffins, means for regulating the temperature of the floor of the coking oven so as to control the coking of said hydrocarbon oil, a refractory off-take duct connecting said oven with said cracking flue for conducting gases and vapors from said oven to said flue, auxiliary refractory heating flues independent of said main oven heating flues and located in the roof of said coking oven and directly underneath said cracking flues to furnish heat thereto and means to control said independent heat to regulate the temperature of the heating flues and of said cracking flues to effect a maximum conversion of said straight chain hydrocarbons into aromatic hydrocarbons containing only a small amount of paraffins.

8. In a refractory cracking and coking oven of the broad rectangular type for the pyrolysis of hydrocarbons including the conversion of straight chain hydrocarbons into aromatic hydrocarbons containing only a small amount of paraffins and the production of coke having a density of at least 2.0, that improvement which comprises a series of separated main refractory heating flues directly below the floor of said coking oven on each longitudinal half thereof and a series of refractory recirculation flues positioned directly below said heating flues so as to communicate therewith at the end portions thereof, means for feeding a hydrocarbon oil onto the floor of said coking chamber, means for regulating the temperature of said floor during operation of the coking chamber between about 1350° F. and 2,000° F., an elongated refractory cracking flue incorporated in the roof above said oven, said cracking flue having walls of refractory material having a multiplicity of projections to cause turbulence of the oil vapors during passage of the vapors in contact therewith, said cracking flue having an extended passage therethrough for the conversion of straight chain hydrocarbons into aromatic hydrocarbons containing only a small amount of paraffins, a refractory off-take duct connecting said oven with said cracking flue for conducting gases and vapors from said oven to said flue, auxiliary refractory heating flues independent of said main oven heating flues and located in the roof of said coking oven and directly below said cracking flues to furnish independent heat thereto, and means to control said independent heat to regulate the temperature of the heating flues so as to provide a temperature between about

1300° F. to 1800° F. in said cracking flues to effect a maximum conversion of said straight chain hydrocarbons into aromatic hydrocarbons containing only a small amount of paraffins.

- 5 9. A refractory cracking and coking oven for the combined pyrolytic treatment of fluid hydrocarbon masses including residual petroleum oil, tar and the like, to convert straight chain hydrocarbons into aromatic hydrocarbons including benzol, toluol, xylol and the like containing a small amount of paraffins, and the carbonization of the residue into coke of high density, which comprises an elongated broad refractory coking oven having a length greater than its width and a height less than its width, a main heating flue system located directly underneath and associated with said coking oven for effectively volatilizing vapors of fluid hydrocarbon masses contained therein and for thoroughly carbonizing residue from said hydrocarbon masses into coke of high density, a recirculating flue operatively associated with said main heating flue system to recirculate gases therein, a refractory vapor cracking flue system associated with the roof of said coking oven for pyrolytically treating hydrocarbon vapors volatilized from said hydrocarbon masses and for converting said vapors from straight chain hydrocarbons into aromatic hydrocarbons including benzol, toluol, xylol and the like, containing a small amount of paraffins, outlet means for removing said treated and converted vapors from said cracking flue system and for conducting said vapors to a by-product recovery system, a controllable auxiliary heating flue system mounted under said cracking flue system and capable of providing a desired and controlled cracking temperature in said cracking flue system, and a recuperator system operatively connected to said main heating flue system for effecting an exchange of heat from said hot products of combustion going from said main heating flue system to a stack to air coming from the atmosphere and going to said main heating flue system to support combustion of fuel therein.
- 40 10. A refractory cracking and coking oven for the combined pyrolytic treatment of fluid hydrocarbon masses including residual petroleum oil, tar and the like, to convert straight chain hydrocarbons into aromatic hydrocarbons including benzol, toluol, xylol and the like containing a small amount of paraffins, and the carbonization of the residue into coke of high density, which comprises an elongated broad refractory coking oven having a length greater than its width and a height less than its width, an oven door mounted at each end of said coking chamber to seal the same from the atmosphere, a main heating flue system located directly underneath and associated with said coking oven for effectively volatilizing vapors of fluid hydrocarbon masses contained therein and for thoroughly carbonizing residue from said hydrocarbon masses into coke, a recirculating flue operatively associated with said main heating flue system to re-circulate gases therein, a refractory vapor cracking flue system associated with the roof of said coking chamber for pyrolytically treating hydrocarbon vapors volatilized from said hydrocarbon masses and for converting said vapors from straight chain hydrocarbons into aromatic hydrocarbons including benzol, toluol, xylol and the like, containing a small amount of paraffins, outlet means for removing said treated and converted vapors from said cracking flue system and for conducting said vapors to a by-product recovery system, a controllable auxiliary heating

flue system mounted under said cracking flue system and capable of providing a desired and controlled cracking temperature in said cracking flue system, and a recuperator system operatively connected to said main heating flue system for effecting an exchange of heat from said hot products of combustion going from said main heating flue system to a stack to air coming from the atmosphere and going to said main heating flue system to support combustion of fuel therein.

11. A refractory cracking and coking oven for the combined pyrolytic treatment of fluid hydrocarbon masses including residual petroleum oil, tar and the like, to convert straight chain hydrocarbons into aromatic hydrocarbons including benzol, toluol, xylol and the like, containing a small amount of paraffins, and the carbonization of the residue into coke of high density, which comprises an elongated broad refractory coking oven having a length greater than its width and a height less than its width, a plurality of inlet pipes connected to and leading into the interior of said coking oven for introducing fluid hydrocarbon masses including residual petroleum oil, tar and the like, a main heating flue system located directly underneath and associated with said coking chamber for effectively volatilizing vapors of fluid hydrocarbon masses contained therein and for thoroughly carbonizing residue from said hydrocarbon masses into coke of high density, a recirculating flue operatively associated with said main heating flue system to recirculate gases therein, a refractory vapor cracking flue system associated with the roof of said coking chamber for pyrolytically treating hydrocarbon vapors volatilized from said hydrocarbon masses and for converting said vapors from straight chain hydrocarbons into aromatic hydrocarbons including benzol, toluol, xylol and the like, containing a small amount of paraffins, starting vapor outlets for removal of vapors at the commencement of the operation of volatilizing vapors from said fluid hydrocarbon masses contained in said coking chamber, outlet means for removing said treated and converted vapors from said cracking flue system and for conducting said vapors to a by-product recovery system, a controllable auxiliary heating flue system mounted under said cracking flue system and capable of providing a desired and controlled cracking temperature in said cracking flue system, and a recuperator system operatively connected to said main heating flue system for effecting an exchange of heat from said hot products of combustion going from said main heating flue system to a stack to air coming from the atmosphere and going to said main heating flue system to support combustion of fuel therein.

12. A cracking and coking oven for the combined pyrolytic treatment of fluid hydrocarbon masses including residual petroleum oil, tar and the like, to convert straight chain hydrocarbons into aromatic hydrocarbons including benzol, toluol, xylol and the like, and the carbonization of the residue into coke, which comprises an elongated broad coking chamber having a length greater than its width and a height less than its width, an oven door mounted at each end of said coking chamber to seal the same from the atmosphere, a plurality of inlet pipes connected to and leading into the interior of said coking chamber for introducing fluid hydrocarbon masses including residual petroleum oil, tar and the like, a main heating flue system associated with said coking chamber for effectively volatilizing vapors

of fluid hydrocarbon masses contained therein and for thoroughly carbonizing residue from said hydrocarbon masses into coke, a recirculating flue operatively associated with said main heating flue system to recirculate gases therein, a vapor cracking flue system associated with the roof of said coking chamber for pyrolytically treating hydrocarbon vapors volatilized from said hydrocarbon masses and for converting said vapors from straight chain hydrocarbons into aromatic hydrocarbons including benzol, toluol, xylol and the like, starting vapor outlets for removal of vapors at the commencement of the operation of volatilizing vapors from said fluid hydrocarbon masses contained in said coking chamber, outlet means for removing said treated and converted vapors from said cracking flue system and for conducting said vapors to a by-product recovery system, a gas main for the removal of vapors coming from said coking chamber and said cracking flue system, a controllable auxiliary heating flue system mounted under said cracking flue system and capable of providing a desired and controlled cracking temperature in said cracking flue system, means to conduct hot waste gas from said auxiliary heating flue system to a pre-heater for preheating the fluid hydrocarbon masses including residual petroleum oil, tar and the like, prior to introducing the same into said coking chamber, and a recuperator system operatively connected to said main heating flue system for effecting an exchange of heat from said hot products of combustion going from said main heating flue system to a stack to air coming from the atmosphere and going to said main heating flue system to support combustion of flue therein.

13. A refractory cracking and coking oven for the combined pyrolytic treatment of fluid hydrocarbon masses including residual petroleum oil, tar and the like, to convert straight chain hydrocarbons into aromatic hydrocarbons including benzol, toluol, xylol and the like containing a small amount of paraffins, and the carbonization of the residue into coke of high density, which comprises an elongated broad refractory coking oven having a length greater than its width and a height less than its width, means provided at each end of said coking chamber and capable of sealing the same from the atmosphere and capable of permitting the removal of coke when said coking chamber is unsealed, means for introducing fluid hydrocarbon masses into said coking chamber, a main heating flue system located directly underneath and associated with said coking oven for effectively volatilizing gases and vapors from fluid hydrocarbon masses contained in said coking oven and for thoroughly carbonizing residue from said hydrocarbon masses into coke, a recirculating flue operatively associated with said main heating flue system to recirculate gases therein, an air inlet connected to the atmosphere to provide air for combustion of fuel in said main heating flue system, a refractory vapor cracking flue system associated with the roof of said coking chamber for pyrolytically treating hydrocarbon vapors volatilized from said hydrocarbon masses and for converting said vapors from straight chain hydrocarbons into aromatic hydrocarbons including benzol, toluol, xylol and the like containing a relatively small amount of paraffins, off-take means connecting said coking oven with said cracking flue system for conducting gases and vapors from said coking oven to said cracking flue, a controllable auxiliary heating flue system mounted under said cracking flue

system and capable of providing a desired and controlled cracking temperature in said cracking flue system, heat exchange means operatively connected to said main heating flue system for effecting an exchange of heat from hot products of combustion going from said main heating flue system to a stack to air coming from the atmosphere and going to said main heating flue system to support combustion of fuel therein, and outlet means for removing from said cracking flue system treated vapors which have been converted from straight chain hydrocarbons into aromatic hydrocarbons including benzol, toluol, xylol and the like and containing a relatively small amount of paraffins.
